UNITED STATES PATENT OFFICE.

ANDREW L. WEIS, OF MONROE, MICHIGAN, ASSIGNOR TO THE WEIS FIBRE CONTAINER CORPORATION, OF MONROE, MICHIGAN, A CORPORATION OF SOUTH DAKOTA.

METAL-BOUND FIBER CONTAINER.

Application filed May 13, 1918. Serial No. 234,150.

To all whom it may concern:

Be it known that I, ANDREW L. WEIS, a citizen of the United States of America, and resident of Monroe, Michigan, have invented a certain new and useful Improvement in Metal-Bound Fiber Containers, of which the following is a specification.

This invention relates to containers of that class in which the walls thereof are formed from sheet material, such as paper or fiber having the requisite strength and thickness, and in which a metal binding is provided for reinforcing the edges of the container.

Generally stated, the object of the invention is to provide a novel and improved metal bound fiber container of the foregoing general character.

A special object is to provide an improved construction and arrangement whereby the metal binding is continuous and unbroken in character, where it extends around the rectangular, round or other shaped ends or heads of the container, whereby the container has an opening provided with a closure, so that the metal binding is all applied and fastened in place before the container is filled, and whereby the container, after being completed and filled, may then be closed and sealed in a convenient and satisfactory way, and in a manner permitting easy opening of the container afterwards when it is desired to remove the contents thereof.

It is also an object to provide certain details and features of construction tending to increase the general efficiency and desirability of a metal bound fiber container of this particular construction.

To these and other useful ends my invention consists in matters hereinafter set forth and claimed, and shown in the accompanying drawings, in which—

Fig. 1 is a perspective of a metal bound fiber container embodying the principles of the invention.

Fig. 2 is a vertical section of said container on line 2—2 in Fig. 3, showing the closure in its raised position in dotted lines.

Fig. 3 is a plan or top view of said container.

Fig. 4 is an enlarged detail section on line 4—4 in Fig. 3.

Fig. 5 is an enlarged detail view looking down on one corner portion of the container.

Fig. 6 is an enlarged detail section on line 6—6 in Fig. 1.

Fig. 7 is a perspective of a portion of the metal binding, showing the same before the bending thereof at the corner of the container.

Fig. 8 is a similar view showing the condition of the metal binding after it is bent to form the corner.

Fig. 9 is a view similar to Fig. 3, showing a different form of the invention.

Fig. 10 is a side elevation of the container shown in Fig. 9, showing a portion of the outside wall broken away and showing certain of the walls in vertical section.

Fig. 11 is an enlarged detail sectional view showing the construction of the bottom of the container shown in Figs. 9 and 10.

As thus illustrated, and referring to Figs. 1 to 8 inclusive, the invention comprises a rectangular body having four sides 1, 2, 3, and 5, formed, preferably, by scoring or bending a sheet of paper or fibrous material to bring the edges thereof together, and at one corner of the container the edge portions are lapped at 5 (see Fig. 6), and the overlapping portions are secured together by staples 6 or by any other suitable means, so that a square tube is formed from one piece of sheet material. The ends or upper and lower heads of the container are countersunk, and are formed, respectively, by upper and lower rectangular sections 7 and 8, which are a little larger than the interior of the container and which have their edges turned outward to form flanges 9 and 10, the edges of these flanges being even or flush with the upper and lower edges of the side walls, 1, 2, 3, and 4, so that the heads or ends are, as stated, countersunk in character.

A continuous strip of metal binding 11 is applied to the rim formed around the top or upper head of the container (see Fig. 4), this binding being formed from sheet metal and bent so that it is U-shaped in cross section, and in this way the two thicknesses of fiber, formed by the flange 9 and the upper edge-portion of the side walls, are clamped tightly between the two thicknesses of metal binding. After its application to the rim or head of the box, the binding is indented at 12 to fasten it in place. It can also be fastened in place by staples or any other suitable means. At the bottom or lower end of the container the flange 10 is secured to

the lower edge-portions of the side walls by the metal binding 13, which is similar to that previously described, and which is secured in place by indentations 14 in the inner and outer metal walls thereof, so that two thicknesses of fiber are clamped tightly together in the hollow or U-shaped metal binding. In this way the container is made perfectly tight at the top and bottom, and all around, and is also very strong. At the corners of the container, the metal binding must be bent, of course, and this can be done, for example, as shown in Figs. 5, 7, and 8, by forming an oblong opening 15 at each corner, before the metal binding is bent, and by allowing the surplus metal 16 inside of each corner to assume the form of a fold (see Fig. 8), so that the hollow binding can be bent easily to form the corner portions thereof. The metal binding can be provided in the form of square hoops, to be slipped over the ends of the container, and thereafter provided with the indentations 12 and 14, thereby to secure the metal hoops in place, or, if desired, the binding can be formed in straight lengths and cut into shorter lengths according to the size of the container, and these short lengths can then be bent around to form the square hoops, and the opposite ends of each short length can then be brought together to form a butt joint or to form a lap joint, and may be secured together, if desired, in any suitable or desired manner. As shown, the binding is in the form of continuous and unbroken square rings or hoops. Sheet steel, of the proper quality, is preferably employed for this binding. Of course, it is obvious that other expedients or features of construction can be employed to permit the bending of the metal binding at the corners of the container, and to take care of the surplus metal at the inner side of each corner, but the method shown will serve the purpose and is illustrative of this feature of the invention. If desired, both the top and the bottom can be reinforced inside thereof, by an extra thickness of fiber or sheet material, such as the square disk or section 17 (see Figs. 2 and 4), secured to the under side of the top section 7 by staples 18, or by any other suitable means; and the similar section 19 can be secured to the bottom section 8 in any suitable or desired manner, thereby reinforcing the top and bottom of the container. It will also be seen that this container is essentially one in which all of the metal binding is applied and secured to the structure before the container is filled, so that no metal binding is applied after the filling of the container, the receptacle or box thus formed being entirely finished before it is filled, notwithstanding the fact that it has countersunk upper and lower ends. For this purpose, therefore, the top section 7 is

preferably formed with a rectangular, centrally located opening 20, which fits the edges of the rectangular closure 21, the latter being cut out from this top section at three sides thereof, but the other side being merely scored or creased to provide a fold line 22 at the rear edge of the cover, it serves as a hinge therefor, so that the cover can be swung up and down. The inner reinforcing section 17 has a rectangular opening 23 which is smaller than the opening 20, so that a ledge or shoulder or lip 24 extends along the four sides of the opening thus formed in the top of the container, upon which the closure 21 rests when in closed position. This opening 23 is formed by cutting out a rectangular section 25 of the sheet material from which the inner section 24 is made, and this section 25 is secured to the cover or closure 21 by staples 26, or by any other suitable means, so that the cover is also of double thickness, and one thickness being of less area than the other, whereby the cover fits both openings. A small notch 27 is preferably formed at one edge of the opening, in the upper thickness thereof, so that the thumb or finger can be inserted against an edge of the cover or closure to open the same. After the receptacle or container is filled, the closure 21 is then swung down into place, and can be secured or fastened in closed position by a sealing strip or sheet of paper or other material, glued or otherwise fastened over the countersunk upper head of the box, or by any other suitable retaining means, it being obvious that various expedients can be employed for sealing the closure of the box or container after the filling thereof is completed. As shown in Figs. 9, 10, and 11, the package or container is similar to the one previously described, but in this case the side walls 28 are round, being in the form of a cylinder or round tube. It will be understood that this drum or tube can be formed in various ways from paper or fiber or other sheet material, and an explanation of the different manufacturing methods by which such drums or tubes are ordinarily made from paper or fiber will not be necessary. The top and bottom of the round or cylindric container thus formed are countersunk like the one previously described, being formed by a top wall 29 of double thickness, if desired, like the one previously described, and by a bottom wall 30 of double thickness, like the one described in connection with the square or rectangular retainer, if a double thickness is necessary or desirable, the two thicknesses being secured together by staples 31 or any other suitable means. In this case, also, the upper and lower metal binding 32 and 33 are in the form of round hoops or rings, and are

slipped over the double thicknesses formed by the flanges on the top and bottom walls and the outer walls of the sides, so that these two thicknesses are compressed together inside of the metal binding by indenting the walls of the binding, or by any other suitable means as previously described. The closure 34 of this cylindric package or container may be exactly like the one described 5 in connection with the square or rectangular container shown in Figs. 1 to 8 inclusive. Of course, with this round or cylindric construction, the metal binding is not formed with corners, and the outer wall of the 10 binding will be stretched, or the inner wall will be compressed, or both, inasmuch as the formation of the hollow strip into rings will result in concentrically raised inner and outer walls of different diameters, there- 15 20 25

by requiring the stretching of the outer wall or a compression or shortening of the inner wall, or both, by any of the ordinary or well known manufacturing methods,—that is to say, by any of the methods known to manufacturers of sheet metal articles of this general character.

In either case, however, the container is constructed from paper or fiber or similar sheet material, and provided with permanent countersunk upper and lower ends reinforced by continuous or practically continuous metal binding, forming the rims of the countersunk heads, and provided in one countersunk head, preferably the upper one, 30 35 40 45 50 55 60 65

with an opening having a closure. The opening, of course, forms a restricted mouth or aperture for the top of the container, inasmuch as this opening is of less area than the diameter or interior of the container, as distinguished from the unrestricted opening which would be formed, for example, by leaving out one head of the container for the filling of the receptacle. In this way the heads are both permanently inserted before the container is filled. The exact thickness and character of the walls of the container will depend, of course, upon the nature of the contents to be placed therein. If it is desired to have the container water- 50 55 60 65 70 75 80 85 90 95 100 105 110 115 120 125

proof or moisture-proof, it can be coated inside and out with paraffin or with other substance which would render the walls impervious to moisture or liquid. The stapling, of course, can be done before the heads are fitted in the ends of the container, and the indenting of the metal binding, to fasten it in place, can be done with a tool or a device of any suitable or desired character, or by machinery. The container, of course, can be of any suitable or desired size, and may be of different proportions, and the two containers shown and described will illustrate the possibility of making the containers of round or square or of any other desired shape or size or form.

The indentations 12 and 14, in the walls of the sheet metal binding, are in the nature of devices which are made by swaging or distorting portions of metal, and which are adapted to pierce or penetrate the fiber 70 of the sheet material from which the walls of the container are made. Staples, or other similar devices, made from bent or swaged or distorted portions of metal, would operate in a similar way,—that is to say, would 75 puncture or pierce or penetrate the fiber of the walls of the container, and in this way the sheet metal binding is fastened to the rims of the heads of the container, by devices of this kind, after the binding is in 80 place.

In either form of the invention the metal binding is bent to extend entirely around the box, as each binding is a single piece of sheet metal, and the bending and shaping 85 is all done before the box is filled.

What I claim as my invention is:—

1. In a metal bound fiber container, side walls of sheet material, countersunk heads of sheet material, metal binding permanently secured to the rims around both of said heads, the upper head having a circumscribed opening therein, forming a restricted mouth for the container, so that the container may be filled after both heads are 95 secured in place, and a closure for said opening, said closure being below the edges of said binding, said countersunk heads being rectangular, and said metal binding being provided with an aperture (15) at each 100 corner to facilitate bending, and having the surplus metal (16) forming a fold inside of each corner.

2. In a metal bound fiber container, side walls of sheet material, countersunk heads 105 of sheet material, metal binding permanently secured to the rims around both of said heads, each binding comprising a single strip of sheet metal extending entirely around the box and joined at its ends, the upper head 110 having a circumscribed opening therein, forming a restricted mouth for the container, so that the container may be filled after both heads are secured in place, and a closure for said opening, said closure being disposed in a plane below the upper edges of said binding, said heads being formed by a plurality of thicknesses of sheet material stapled together, and only the single outer thickness of each head being ex- 115 tended within the metal binding, leaving the other thicknesses of the heads outside of said binding.

3. In a metal bound fiber container, a hollow binding strip having an aperture (15) 120 to facilitate bending thereof around a corner of the container, said binding being U-shaped in cross section, with said aperture in the portion between the two sides of the binding.

4. In a metal bound fiber container, a metal binding strip of double thickness, being U-shaped in cross section so that the two thicknesses are spaced apart, having an aperture (15) in a corner portion thereof, and having the surplus metal forming a fold (16) immediately inside of the corner adjacent said aperture.
5. In a metal bound fiber container, the combination of fiber sheet material to form side walls, fiber sheet material to form an end wall, with the edge portions of said walls forming a rim having corners, and a sheet metal binding bent to extend entirely around the box and enclosing said rim, with an opening in the metal binding at each corner of the rim, to facilitate bending of the binding, and with the surplus metal produced by bending the binding at the corners forming a fold at one edge of each opening and inside of each corner.
6. In a metal bound container having a corner, a binding strip extending around said corner, said strip comprising two thicknesses spaced apart to enclose the corner portion of the container, with an opening in the binding at the corner, and with the surplus metal of the inner thickness forming a fold at one edge of each opening and inside of said corner, said opening being formed in the metal between the two thicknesses of the binding.

Signed by me at Monroe, Michigan, this 29th day of April, 1918.

ANDREW L. WEIS.
